SEPARABLE FASTENER

Davis Marinsky, Bronx, N. Y., assignor to White-hall Patents Corporation, New York, N. Y., a corporation of New York

Application October 22, 1936, Serial No. 106,961

13 Claims. (Cl. 24—205)

This invention relates to separable fasteners employing stringers having interengaging links with a slider movable along the stringers to couple and uncouple the links, and particularly, 5 to an improved end stop and slider construction for devices of the kind under consideration; and the object of the invention is to provide a fastener of the class described with an end stop consisting of detachably coupled parts with means 10 on said end stop and slider for retaining the slider and one part of the end stop against disengagement when the separate parts of the end stop are detached; a further object being to provide means involving said coupling or retaining 15 means for supporting the slider in proper alignment with the end stop part to facilitate engagement and disengagement of the removable end stop part or pin so as to provide free and positive action in coupling and uncoupling the 20 stringers; a further object being to provide a slider and the end stop part to which the slider is adapted to be coupled one with a spring and the other with a part engaged by said spring to couple or latch said parts when in juxtaposition 25 or abutting position and still further to the provision of means for disengaging or unlatching the slider with said part in the operation of coupling the other of said end parts with the first named part prior to the coupling of the stringers 30 by movement of the slider longitudinally thereof and away from said end stop; and with these and other objects in view, the invention consists in a device of the class and for the purpose specified, which is simple in construction, efficient in use 35 and which is constructed as hereinafter described and claimed.

The invention is fully disclosed in the following specification, of which the accompanying drawing forms a part, in which the separate 40 parts of my improvement are designated by suitable reference characters in each of the views, and in which:

Fig. 1 is a plan and sectional view of one end 45 portion of a separable fastener with the slider arranged in spaced relation to the end stop employed.

Fig. 2 is a partial section on the line 2—2 of Fig. 1 with one of the stringers detached.

Fig. 3 is a view of the opposite side of the end 50 of the fastener shown in Fig. 1 with parts in a different position.

Fig. 4 is a section on the line 4—4 of Fig. 3.

Fig. 5 is a section on the line 5—5 of Fig. 3, 55 indicating one of the stringers partly detached

and showing the slider in coupled or latched position.

Fig. 6 is a view similar to Fig. 3 showing a modification; and,

Fig. 7 is a section substantially on the line 5 1—7 of Fig. 6.

In separable fasteners of the kind described, several problems have been experienced, especially in devices of this kind as applied to shirts, lumber jackets and similar kinds of installations 10 where it is desirable to completely separate the stringers. With these types of devices, what are known as detachably coupled end stops are employed at one end of the stringers and difficulty has been experienced in properly coupling the 15 separate parts of the end stop especially when passed through a slider disposed adjacent one of the end stops. On many occasions, the several parts have jammed and become inoperative which is inconvenient for the user, especially because 20 of the difficulty in maintaining the several parts in proper relative position to facilitate the coupling which is necessary to provide the proper intermeshing of the links of the stringers.

It is the purpose of my invention to render 25 devices of this kind more fool-proof by eliminating the possibility of faulty coupling of the stringers in the provision of means for latching or retaining the slider against displacement from one of the end stop parts and to maintain 30 the slider in constant engagement with said part so as to insure and simplify the recoupling of the end stop parts as well as to maintain the slider and first named part in alignment to insure free passage of the second end stop part 35 through the slider and first named part. The structure shown and described herein constitutes an improvement of the structure disclosed in my earlier application, Serial Number 78,604, filed May 8, 1936.

In Figs. 1 to 5 inclusive, I have shown one method of carrying my invention into effect, and in these figures I have shown parts of one end portion of stringers 10 and 11 having coupling links or scoops 12 and 13 arranged longitudinally 45 of one edge portion thereof and adapted to be coupled and uncoupled by a slider 14 movable longitudinally thereof as in other devices of this kind.

The end portion of the fastener disclosed is 50 adapted to be coupled and uncoupled by means of a detachable end stop consisting in the construction shown of a U-shaped part 15 having an elongated bar 16 arranged and secured in one side of the channel 17 of said part, the bar por- 55

tion 16 projecting beyond the inner end of the U-shaped part 15 as seen at 16a. The inner side surface of the bar portion 16 is provided with longitudinally spaced notches or recesses 16b. The other part 18 of the end stop is in the form of an elongated pin or bar substantially similar to the bar 16 and this part is provided with spaced knobs 18a adapted to enter the notches or recesses 16b to couple said parts together, it being understood at this time that the part 18 may be recessed and the bar portion 16 provided with the projections, if desired. The ends of the stringers 10 and 11 or that portion thereof to which the bars 16 and 18 are secured are preferably reinforced in any suitable manner. In the construction shown, sheet metal plates 19 and 19a are employed and these plates extend around the beaded edges 10a, 11a of the stringers 10 and 11 within the bars 16 and 18 as indicated in Fig. 4 of the drawing.

The pin part 18 is insertable into the channel 17 of the U-shaped part 15 at one side of the bar 16 and projects from the part 15 in substantially parallel relation to and in alignment with the projection 16a. The U-shaped part 15 has in-turned flanges 15a at its side edges and these flanges serve to retain the pin 18 against lateral displacement from the part 15, and the space between the flanges will receive the stringer tapes 30 including the plates 19, 19a arranged thereon. Arranged on the rear side surface of the part 15 is a spring plate or arm 20 which may be riveted or otherwise secured in position as seen at 21, and if desired, this plate may be countersunk in said surface of the part 15. The end portion 22 of the part 20 projects beyond the end wall 23 of the part 15 which wall forms a stop wall against which the end of the slider 14 abuts; and said projecting end 22, in the construction shown in Figs. 1 to 5 inclusive, is provided with an aperture 24 adapted to receive a projecting pin or other member 25 on the corresponding surface of the slider 14 when the latter is in abutting relation to the end wall 23 of the member 15 as seen in Fig. 5 of the drawing. The end portion 22 of the spring 20 is preferably flared outwardly in order to provide free movement of the end of the slider beneath said spring as the slider advances in the direction of the end stop.

Adjacent the attached end of the spring 20 is an inwardly projecting portion or pin 26 which passes through an aperture 27 formed in the part 15 and is adapted to project into that part of the channel 17 into which the pin part 18 passes. The arrangement of the projection 26 and the part 18 will be such that in moving said part 18 into the part 15, the projection 26 will be engaged to move the spring 20 outwardly and disengage the same from the projection or pin 25 on the slider and thus permit the movement of the slider longitudinally of the stringers away from the end stop in coupling the links 12 and 13 of the stringers, it being understood that when the part 18 is detached from the part 15, the spring 20 will be in engagement with the pin or projection 25 to hold and retain the slider 14 against displacement from the part 15 and at the same time will operate to hold the end of the slider in abutting engagement with the stop wall 23, thus maintaining the slider in proper position to facilitate free and non-binding insertion and removal of the pin part 18 with respect to the slider and the part 15. The slider 14 includes a finger piece or pull 27 which is pivoted or otherwise coupled to the front face of the slider as indicated at 28.

In the construction shown in Figs. 6 and 7 of the drawing, I have illustrated a slight modification wherein a spring arm or coupling 29 is substituted for the arm 20, the arm 29 being of narrow construction to illustrate that it is not essential to employ the wide arm shown in Fig. 3. With this construction, the slider 14a is provided with an aperture or recess 30 adapted to receive a pin or projection 31 at the free end portion of the arm 29 which simply amounts to a reversal of the aperture 24 and pin 25 shown in Figs. 2 and 5. The structure shown in Figs. 6 and 7 also includes an inwardly projecting pin 26a similar to the pin 26 which passes through an aperture in one side wall of the U-shaped body 15a to be engaged by the pin part 18' to move the pin 31 out of the aperture 30 of the slider 14a to permit longitudinal movement of the slider on the stringers in coupling the same.

In the construction shown, the slider coupling or latching means has been incorporated in connection with a molded or die cast body of a detachable end stop, but it will be understood that the same may be incorporated in conjunction with or as a part of other types and forms of end stops as well as in sliders of various types and constructions. The distinctive feature of the present invention resides in the provision of means on an end stop and a slider movable toward and from the end stop for positively coupling or latching the slider with the end stop to retain the slider against displacement therefrom, especially when the stringer parts are detached or separated. It will be understood in this connection that the slider will be uncoupled or unlatched by the insertion of the pin member into the socket portion of the end stop to which the slider is coupled. It is also desirable to provide relatively wide abutting surfaces on the slider and end stop so that in coupling the slider with the end stop, proper alignment of the slider with the end stop may be maintained to facilitate insertion and removal of the pin part.

Having fully described my invention, what I claim as new and desire to secure by Letters Patent, is:

1. In separable fasteners employing stringers and a slider movable longitudinally on the stringers for coupling and uncoupling the same, an end stop at one end of the stringers limiting the movement of the slider in the direction of said end of the stringers, a yielding coupling part arranged upon the outer surface of said end stop and extending longitudinally thereof with the free end of said part projecting onto the stringer beyond the body portion of said end stop, the free end of said yielding part and slider being provided one with a projection and the other with an aperture receiving the projection for coupling the slider to said stop to prevent displacement of the slider therefrom, and means movable relatively to the end stop and cooperating with the yielding part thereof for controlling the coupling and uncoupling of the slider with said end stop.

2. In separable fasteners employing stringers and a slider movable longitudinally on the stringers for coupling and uncoupling the same, an end stop at one end of the stringers limiting the movement of the slider in the direction of said end of the stringers, a yielding coupling part arranged upon the outer surface of said end stop and extending longitudinally thereof with the free end of said part projecting onto the stringer beyond the body portion of said end stop, the free end of said yielding part and slider being provided one

with a projection and the other with an aperture receiving the projection for coupling the slider to said stop to prevent displacement of the slider therefrom, and means movable relatively to the end stop and cooperating with the yielding part thereof for controlling the coupling and uncoupling of the slider with said end stop, said last named means comprising a pin part on one of the stringers detachable with respect to the end stop and slider in uncoupling or separating the fastener stringers.

3. An end stop for separable fasteners employing stringers and a slider movable longitudinally of the stringers to couple and uncouple the same, said end stop being disposed at one end of the stringers, a spring arm on said stop, the free end portion of which projects beyond the inner end of the stop, the free end of said spring arm having an aperture, said end stop comprising a U-shaped body having a channel longitudinally of one side portion thereof, and said spring arm having a projecting portion adapted to extend into said channel in one position of said arm.

25 4. An end stop for separable fasteners employing stringers and a slider movable longitudinally of the stringers to couple and uncouple the same; said end stop being disposed at one end of the stringers, a spring arm on said stop, the free end portion of which projects beyond the inner end of the stop, the free end of said spring arm having an aperture, said end stop comprising a U-shaped body having a channel longitudinally of one side portion thereof, said 30 spring arm having a projecting portion adapted to extend into said channel in one position of said arm, the channel of said end stop being attached to one of the fastener stringers and a pin part on the other fastener stringer insertable into the channel of said body and cooperating with the projection on said arm to move the arm outwardly with respect to one side surface of said body.

5. In separable fasteners employing stringers with a slider movable longitudinally of the stringers to couple and uncouple the same, a detachable end stop at one end of the stringers, said end stop comprising a U-shaped part attached to one stringer with a channel portion of said part disposed outwardly of one edge of the stringer, a pin part on the other stringer insertable into the channel of the first part in coupling the end stop and said end of the stringers, said first named part having a spring member mounted upon one side face thereof, said member having a projection normally extending into the channel of said part by the spring properties of said member, said member and the slider of said stringers having interengaging couplings for latching and retaining the slider against displacement from the first named part when in juxtaposition thereto and when the pin part is detached from said first named part.

6. In separable fasteners employing stringers with a slider movable longitudinally of the stringers to couple and uncouple the same, a detachable end stop at one end of the stringers, said end stop comprising a U-shaped part attached to one stringer with a channel portion of said part disposed outwardly of one edge of the stringer, a pin part on the other stringer insertable into the channel of the first part in coupling the end stop and said end of the stringers, said first named part having a spring member mounted upon one side face thereof, said 75 member having a projection normally extending

into the channel of said part by the spring properties of said member, said member and the slider of said stringers having interengaging couplings for latching and retaining the slider against displacement from the first named part when in juxtaposition thereto and when the pin part is detached from said first named part, and said pin part engaging the projection on said member in the insertion of the pin part into the first named part to move said member into position 10 to unlatch the slider from said first named part.

7. In detachably coupled end stops for separable fasteners, a U-shaped die cast body forming one part of the end stop and secured to one of the fastener stringers with a channeled portion of said part disposed longitudinally of one side edge of the stringer, a pin part on the other stringer insertable into the channel of the first named part, a flat spring secured at one end to one side surface of the first named part, 15 the free end of said spring projecting beyond the inner end of the channeled portion of said part, said spring having a projection extending through the side wall of said first named part into the channel thereof and adapted to be engaged by the pin part when inserted into the channel to move said spring outwardly with respect to the side surface of said first named part.

20 8. In detachably coupled end stops for separable fasteners, a U-shaped die cast body forming one part of the end stop and secured to one of the fastener stringers with a channeled portion of said part disposed longitudinally of one side edge of the stringer, a pin part on the other 25 stringer insertable into the channel of the first named part, a flat spring secured at one end to one side surface of the first named part, the free end of said spring projecting beyond the inner end of the channeled portion of said part, 30 said spring having a projection extending through the side wall of said first named part into the channel thereof and adapted to be engaged by the pin part when inserted into the channel to move said spring outwardly with respect to the side surface of said first named part, and the 35 free end portion of said spring having latching means for engaging the slider when arranged in juxtaposition to said first named part.

40 9. In detachably coupled end stops for separable fasteners, a U-shaped die cast body forming one part of the end stop and secured to one of the fastener stringers with a channeled portion of said part disposed longitudinally of one side edge of the stringer, a pin part on the other 45 stringer insertable into the channel of the first named part, a flat spring secured at one end to one side surface of the first named part, the free end of said spring projecting beyond the inner end of the channeled portion of said part, said 50 spring having a projection extending through the side wall of said first named part into the channel thereof and adapted to be engaged by the pin part when inserted into the channel to move said spring outwardly with respect to the side surface of said first named part, the free 55 end portion of said spring having latching means for engaging the slider when arranged in juxtaposition to said first named part, and part of said spring being countersunk in the side surface of said first named part.

60 10. In detachably coupled end stops for separable fasteners, a U-shaped die cast body forming one part of the end stop and secured to one of the fastener stringers with a channeled portion of said part disposed longitudinally of one 65

side edge of the stringer, a pin part on the other stringer insertable into the channel of the first named part, a flat spring secured at one end to one side surface of the first named part, the 5 free end of said spring projecting beyond the inner end of the channeled portion of said part, said spring having a projection extending through the side wall of said first named part into the channel thereof and adapted to be engaged 10 by the pin part when inserted into the channel to move said spring outwardly with respect to the side surface of said first named part, the free end portion of said spring having latching means for engaging the slider when arranged 15 in juxtaposition to said first named part, part of said spring being countersunk in the side surface of said first named part, said first named part having a pin portion arranged parallel to the pin part when the stringers are coupled together, and said pin portion and pin part having 20 means preventing lateral movement with respect to each other outwardly of the channel portion of the first named part.

11. In separable fasteners employing stringers and a slider movable longitudinally of the stringers for coupling and uncoupling the same, an end stop at one end of the stringers limiting the movement of the slider in the direction of said end of the stringers, said stop comprising a 25 socket member secured to one stringer and a pin member secured to the opposed stringer, said pin member being insertable into and removable from the socket of the socket member, a yielding coupling part on said socket member, an element 30 on said yielding part and projecting into the socket of said socket member, said pin member engaging said element when inserted into the socket member, and said yielding part and slider being provided, one with a projection and the 35 other with an aperture receiving said projection for coupling the slider with said socket member to prevent displacement of the slider therefrom when said pin member is removed from the socket member.

40 12. In separable fasteners employing stringers and a slider movable longitudinally of the stringers for coupling and uncoupling the same, an

end stop at one end of the stringers limiting the movement of the slider in the direction of said end of the stringers, said stop comprising a socket member secured to one stringer and a pin member secured to the opposed stringer, said 5 pin member being insertable into and removable from the socket of the socket member, a yielding coupling part on said socket member, an element 10 on said yielding part and projecting into the socket of said socket member, said pin member engaging said element when inserted into the socket member, said yielding part and slider being provided, one with a projection and the other with an aperture receiving said projection 15 for coupling the slider with said socket member to prevent displacement of the slider therefrom when said pin member is removed from the socket member, and said socket member having projecting portions engaged by said slider in maintaining lateral alignment of the slider with 20 said socket member when coupled therewith.

13. In separable fasteners employing stringers and a slider movable longitudinally of the stringers for coupling and uncoupling the same, an end stop at one end of the stringers limiting the movement of the stringers in the direction of said end of the stringers, said end stop comprising a socket member secured to one stringer and a pin member secured to the opposed stringer, means for coupling the slider with the socket 25 member when the slider is in abutting relation therewith, said means comprising a resilient part projecting from the socket member onto the stringer and adapted to overlap the end portion 30 of the slider when moved into engagement with said socket member, said resilient part and slider being provided one with a projection and the other with an aperture receiving said projection in coupling the slider with said socket member, coupling means on said resilient part projecting 40 into said socket member and said pin member when inserted into the socket of the socket member engaging said projecting means to move said resilient part into position disengaging the slider to permit movement of the slider out of engagement with the socket member.

DAVIS MARINSKY.
